UNITED STATES PATENT OFFICE.

GEORGE DEWEY LOCKWOOD AND WALTER H. WAKEFIELD, OF WORCESTER, MASSACHUSETTS, ASSIGNORS TO CROMPTON & KNOWLES LOOM WORKS, OF WORCESTER, MASSACHUSETTS, A CORPORATION OF MASSACHUSETTS.

TUBE FRAME FOR AXMINSTER LOOMS.

Application filed November 19, 1923. Serial No. 675,470.

To all whom it may concern:

Be it known that we, GEORGE D. LOCKWOOD and WALTER H. WAKEFIELD, citizens of the United States, both residing at Worcester, in the county of Worcester and State of Massachusetts, have invented a new and useful Tube Frame for Axminster Looms, of which the following is a specification.

This invention relates to tube frames for Axminster looms and more particularly to the construction of the brackets by which the tube frames are connected to the chains ordinarily found in this type of loom.

An object of the invention is to provide a tube frame having a spool bearing formed with an integral tongue which is secured directly to a portion of the bar comprising the yarn tube supporting portion of the tube frame, the spool bearing being embraced by a pair of ears formed with the bar and serving to prevent movement of the spool bearing longitudinally of the tube frame.

A further object of the invention is to provide a bracket with a chain engaging portion which shall be readily removable from the tube frame only in a direction substantially at right angles to the line of strain to which the bracket is subjected when supporting the tube frame in the chain.

A further object of the invention is to provide a tube frame with spool bearing and chain engaging portions each of which shall have interengaging members by means of which each part will brace the other against relative lateral motion, the parts being held together by removable means.

With these and other objects in view which will appear as the description proceeds, our invention resides in the arrangement and combination of parts hereinafter described and set forth in the claims.

In the accompanying drawings—

Fig. 1 is a side elevation of one end of a tube frame embracing our invention,

Fig. 2 is an end view of the structure shown in Fig. 1 with the spool omitted,

Fig. 3 is a perspective view of the lower end of the spool bearing member,

Fig. 4 is a view similar to Fig. 3 but showing the lower end of the chain engaging member, and

Fig. 5 is a perspective view of one end of the tube frame before the bracket is applied thereto.

Referring more particularly to the drawings, it will be seen that the tube frame is formed of a hollow tubular bar 10 to which are secured the yarn tubes 11 held thereto by means of angle strip 12 in any approved manner. A spool 13 of the usual construction has a gudgeon 14 which is received in the spool bearing 15.

One feature of our invention concerns the spool bearing member 16, the lower end of which is formed as indicated in Fig. 4 with the tongue 17 projecting somewhat below the shoulders 18 formed on the bottom of the spool bearing member. The lower portion of the tube frame 10 is provided with a slot 19 into which the tongue 17 extends and in which said tongue is riveted. Extending from the vertical walls of the tube frame 10 are ears 20 which are bent inwardly toward each other and lie beyond the vertical plane of the slot 19. The ears 20 pass around the outer face of the spool bearing member 16 and together with the tongue 17 serve to hold said member rigidly to the bar 10.

The bottom and lower portions of the side walls of the tubular bar are extended as indicated at 21 to give lateral support to the lower end of the chain engaging member 22 and also to afford a smooth bottom for the tube frame and to protect the member 22. The latter member is reduced as at 23 to accommodate the ears 20 and has a relatively thicker portion defining a rib 24 the upper edge of which lies under and engages the ears 20 as indicated in Fig. 1.

The chain engaging member 22 is provided with a slot 25 through which extends the usual chain engaging spring member 26. The slot 25 extends downwardly somewhat along the vertical inner portion of the chain engaging member 22 and in order to give lateral support to the latter member we strike up a tongue 27 from the member 16 so proportioned and positioned as to lie in the bottom of the slot 25, thereby preventing side motion of the bracket forming members with respect to each other. Screws 28, located between rib 24 and tongue 27, are provided to extend through the chain en-

gaging member into the spool bearing member to provide detachable means by which member 22 may be removed from the tube frame.

5 It will be seen from an inspection of Fig. 5 that the bottom of the tube frame extends beyond the slot 19 as at 29 and when it is desired to remove the spool bearing member the tube frame may be inverted and 10 supported on any convenient ledge (not shown) to support the tubular member while the tongue is being forced out of the slot 19.

From the foregoing it will be apparent 15 that we have provided a tube frame where-
in the spool bearing member is riveted di-
rectly to the tubular bar and held thereto
by embracing ears; that the chain engag-
ing member is not only readily removable
from the tube frame but is held against
20 transverse motion with respect to the tubu-
lar bar 10 and the spool bearing member
16 by means of the extended side portions
21 and the tongue 27, and that the rib 24
of the chain engaging member is positioned
25 to engage the lower edge of the ears 20.

We have shown herein a construction
wherein the chain engaging member is re-
duced in thickness at the lower end there-
of but we do not wish to be limited to this
30 construction, as it is possible to form this
member of material of uniform thickness
throughout its length.

Having thus described our invention it
will be evident that changes and modifica-
35 tions may be made therein by those skilled
in the art and we do not wish to be limited
to the details herein disclosed but what we
do claim is:

1. In a tube frame for Axminster looms,
40 a hollow tubular bar, a spool supporting
bracket member having the lower end
formed with a tongue integral therewith
and extending into an opening in the bar
45 and expanded in said opening, to prevent
vertical transverse movement of the member
with respect to the bar, means integral with
the bar to limit longitudinal and horizontal
transverse movement of the bracket mem-
50 ber relative to the hollow bar and a chain
engaging member carried by the spool
bearing member.

2. In a tube frame for Axminster looms,
55 a hollow tubular bar, a spool bearing mem-
ber having an integral tongue extending
therefrom into an opening, in one wall of
the bar and expanded into said opening to
hold said member to the bar, ears formed
integral with the hollow tubular bar and
surrounding a portion of the spool bearing
60 member, and a chain engaging member held
to the spool bearing member and having
a portion lying under said ears.

3. In a tube frame for Axminster looms,
a hollow tubular bar, a spool bearing mem-
ber having an integral tongue extending 65
into an opening in one wall of the bar and
expanded in said opening to hold said mem-
ber to said bar, said wall being extended
beyond the said member, to form means ad-
jacent the member by which said bar may 70
be supported when removing the riveted
portion of the member, and a chain engag-
ing member having a portion guarded by
said extension of the said wall and secured
to said first named member. 75

4. In a tube frame for Axminster looms,
a yarn tube supporting bar, a spool bearing
member secured to the bar, means on said
bar projecting beyond the spool bearing
member and presenting a lifting edge, a 80
detachable chain engaging member at-
tached to said first named member, and a
rib formed on said chain engaging member
and lying under the lifting edge, and a
chain hook member carried by said chain 85
engaging member.

5. In a tube frame for Axminster looms,
a hollow tubular bar, a spool bearing mem-
ber, means to secure the member to the bar
including ears integral with the bar and 90
extending around a portion of said member,
a chain engaging member, detachable
means to secure the second member to the
first, a rib on said chain engaging member
lying under said ears, and a chain hook 95
secured to the chain engaging member, said
rib supporting the bar independently of the
detachable means.

6. In a tube frame for Axminster looms,
a hollow tubular member, a spool bearing 100
yarn tube supporting bar, secured thereto,
a detachable chain engaging member at-
tached to the spool bearing member, and
means rigid with and projecting from one
105 of said members and extending into a slot
formed in the other member to prevent
relative transverse movement of said mem-
bers.

7. In a tube frame for Axminster looms,
a yarn tube supporting bar, a spool bearing 110
member secured to said bar, a chain engag-
ing member, means for detachably securing
the chain engaging member to the spool
bearing member, and means extending from
the first named member across the plane of 115
the other member to engage said other mem-
ber and prevent relative transverse move-
ment of said members independently of said
detachable securing means.

In testimony whereof we have hereunto 120
affixed our signatures.

GEORGE DEWEY LOCKWOOD.
WALTER H. WAKEFIELD.
